UNITED STATES PATENT OFFICE.

FRIEDRICH KRAUSS, OF MUNICH, GERMANY.

OXYACETYLENE AND SIMILAR BURNER.

1,095,580.

Specification of Letters Patent.

Patented May 5, 1914.

Application filed April 16, 1912. Serial No. 691,233.

To all whom it may concern:

Be it known that I, FRIEDRICH KRAUSS, citizen of Austria, residing at Munich, Bavaria, Germany, formerly of Vienna, Austria-Hungary, have invented certain new and useful Improvements in Oxyacetylene and Similar Burners, of which the following is a specification.

My invention relates to oxy-acetylene and similar burners, by means of which an intensely hot flame may be produced. In burners of this type, it is the general practice to supply oxygen to the flame after ignition of the inflammable gas in the air, and as a result of this practice very considerable quantities of soot are deposited on the walls of the conduits before the oxygen is admitted, particularly if a carbonaceous gas, such as acetylene, be employed. This deposit detrimentally affects the action of the burner, and causes the dissemination of noxious odors in any inclosure wherein the burner is used. Such soot deposit also frequently causes back flash of the flame, resulting in premature ignition.

The principal object of my invention is to eliminate, in a burner of this type, the disadvantages above referred to, and I purpose to accomplish this object by providing suitable means for excluding atmospheric air from the gas conduit as soon as the fuel supply of oxygen is permitted to flow to the flame. The means which effect this operation may be so constructed as to admit atmospheric air to the gas conduit immediately upon stoppage of the oxygen supply.

The invention includes the novel structural features and combinations of parts hereinafter particularly claimed, and fully described in the following specification, reference being had to the accompanying drawing, wherein—

Figure 1 is a fragmentary elevational view, illustratively embodying one form of the invention; Fig. 2 is a similar view of a somewhat modified form, intended particularly for use as a torch or blow pipe for welding metal; and Fig. 3 is a vertical sectional view of a further modified form of the invention.

In each of the forms of invention illustrated, gas is conducted to the flame from a suitable source through one pipe or conduit, and oxygen through a different pipe, and means are provided whereby when the full supply of oxygen is permitted to flow to the

flame, atmospheric air is excluded from the gas conduit while when the flow of oxygen is stopped no impediment is offered to the admission of atmospheric air to the gas conduit.

Referring to the drawing, and particularly to Fig. 1 thereof, A denotes the gas conduit provided intermediate its ends with one or more orifices a. The perforated tube A constitutes, in effect, a Bunsen burner. It will be understood that at one end the tube A communicates with a source of gas (not shown) and at the opposite end supplies the gas to a burner tip or nozzle (not shown). Rotatably mounted on the tube A, is a sleeve B having orifices therein which are adapted to register with the orifices in the tube A. The sleeve B is provided with, or has formed integrally therewith, a rack F preferably circular in form, for a purpose to be presently described. Arranged adjacent the Bunsen tube A, is a tube or pipe o, one end of which opens into the tube A, and the other end of which is in communication with a source of oxygen under pressure (not shown). The tube o is provided to supply oxygen to the flame. The passage of oxygen through the tube o into the tube A is controlled by a valve 10, the stem 11 thereof having fixed to one end a pinion E meshing with the rack F, and to the other end a handle C by means of which the valve 10 may be operated. When the valve 10 is turned by the handle C to permit oxygen to flow through the pipe o into tube A, the pinion E will be revolved, causing the sleeve B to rotate until its intact portions entirely or partially cover the orifices a in the tube B. By entirely closing these orifices, atmospheric air is excluded from the Bunsen tube, and sooting is thus eliminated. Upon movement of the valve 10 to entirely close off the flow of oxygen, the sleeve B is rotated in the opposite direction, so that the orifices therein register with the orifices in the tube A and an adequate supply of atmospheric air may flow into the latter. By reason of this arrangement, it will be apparent that the device may be employed either as an ordinary Bunsen burner, or as a burner in which gas and oxygen under pressure may be burned. It will, of course, be apparent that the device may be so operated as to only partially open the valve 10 which will result in only partially closing the orifices a in tube A, and conversely, by only partially

5 closing the valve 10 the orifices α will be only partially uncovered. In this manner the quantity of atmospheric air flowing to the Bunsen tube may be accurately proportioned to the quantity of oxygen supplied to the flame, or in other words, the orifices α provide an adjustable auxiliary air supply means for a burner of this type.

10 In the form of invention shown in Fig. 2, A is the Bunsen tube provided with orifices α , and B' is a sleeve having orifices adapted to register with those in the tube A. The sleeve B is provided with a longitudinal, vertically extending rack K, in mesh with a 15 pinion Z carried on the stem of the valve L which governs the flow of oxygen through the pipe o'. The valve L is actuated by the handle G.

20 The operation of the modified form of invention just described is similar to that of Fig. 1, except that the sleeve B' is reciprocated vertically, instead of being rotated, to open and close the orifices α in the Bunsen tube A.

25 In Figs. 1 and 2, I have shown a manually operable valve for controlling the outflow of oxygen, and for actuating the sleeves B, while in Fig. 3 the valve acts entirely automatically, and the movement of the sleeve B being dependent on that of the valve is also automatic.

30 Referring to Fig. 3; A' designates the Bunsen tube having the orifice α' therein, and B² is the sleeve having an orifice α^2 therein. The lower end of the oxygen tube o' opens into the lower end of a two part valve casing Z', divided interiorly by an approximately central diaphragm D of flexible material. The valve casing Z' communicates, 35 by means of a flexible tube or hose W, with a source of oxygen (not shown). Projecting from the sleeve B substantially at right angles to the axis thereof is an arm 12, near the outer end of which is secured a stem u, 40 passing vertically through approximately the central part of the valve casing Z'. At its lower end, the stem u is provided with a conical valve plug N adapted to engage the seat x into which the admission end of the 45 pipe o' opens. The valve plug is normally forced against the seat x by a spiral spring S encircling the upper part of the valve stem u, one end of said spring engaging the upper inner part of the valve casing Z' and 50 the other end pressing downwardly on a collar T carried by the stem u intermediate its ends. When there is no flow of oxygen 55 through the tube W into the chamber M of the valve casing the spring S will maintain 60 the valve plug N against its seat x, whereby the sleeve B² will be in its lowermost position, the orifice α^2 thereof registering with the orifice α' in the tube A' and admitting 65 atmospheric air to the latter. As soon as oxygen is admitted to the valve casing Z' the

70 pressure in the chamber M will increase sufficiently to raise the diaphragm D against the tension of spring S. By raising the diaphragm, the stem u is also raised, unseating the plug N whereby oxygen is permitted to flow into the pipe o', and elevating the sleeve B² so that an intact portion thereof either entirely or partially covers the orifice α' in the tube A' thus reducing or entirely cutting off the supply of atmospheric air to the latter. When the oxygen supply to tube W is discontinued the spring S will again depress stem u, seating the plug N and by lowering the sleeve B² cause the orifices α' and α^2 to register.

75 I desire it to be understood that while I have described my invention in considerable detail, the same is susceptible of modification, without departing from the spirit of the invention as defined by the scope of the 80 appended claims.

85 What I claim is:

1. A burner of the character specified, embodying therein a gas conduit, an oxygen conduit, means for controlling the flow 90 of oxygen through said oxygen conduit, means for supplying air to the gas conduit and means actuated from said first named means for controlling the flow of atmospheric air to said gas conduit.

95 2. A burner of the character specified, embodying therein a gas conduit having orifices through which air may be supplied to said gas conduit, an oxygen conduit, means for controlling the flow of oxygen through 100 said oxygen conduit, and a sleeve operable by the movement of said means to cover or uncover the orifices in said gas conduit to control the flow of atmospheric air to the latter.

105 3. A burner of the character specified, embodying therein a gas conduit having orifices through which air may be supplied to said gas conduit, an oxygen conduit, a valve for controlling the flow of oxygen through said oxygen conduit, a sleeve movable on said gas conduit for covering or uncovering the orifices therein, and means interposed between said sleeve and said valve and actuated by the latter for closing said orifices when said oxygen conduit is opened by the valve, and opening said orifices when said oxygen conduit is closed by the valve.

110 4. A burner of the character specified, embodying therein a gas conduit, means for supplying air to the gas conduit, means for controlling the flow of atmospheric air thereto, an oxygen conduit, a valve controlling the flow of oxygen through said oxygen conduit, and means operable upon increase of pressure in said valve to actuate said second named means to allow atmospheric air to flow into said gas conduit.

115 5. A burner of the character specified, embodying therein a gas conduit, an oxygen 120

conduit, an automatically operating valve for controlling the flow of oxygen through said oxygen conduit, means for supplying air to said gas conduit and means actuated 5 by the movement of said valve for controlling the flow of atmospheric air to said gas conduit.

6. A burner of the character specified, embodying therein a gas conduit, an oxygen 10 conduit, an automatically operating valve for controlling the flow of oxygen through said oxygen conduit, means for normally closing said valve, means for supplying air to said gas conduit and means connected to 15 said valve for controlling the flow of atmospheric air to said gas conduit.

7. A burner of the character specified, embodying therein a gas conduit, an oxygen conduit, a valve casing in communication 20 with one end of said oxygen conduit, means for supplying air to said gas conduit, means movable on said gas conduit for controlling the flow of atmospheric air thereto, a stem in said casing and connected to said second 25 named means, and means within said casing and adapted to be actuated by the pressure therein for actuating said stem to move said second named means on said gas conduit.

8. A burner of the character specified, 30 embodying therein a gas conduit having orifices through which air may be supplied to said gas conduit, an oxygen conduit, a valve casing having therein a valve seat into which one end of the oxygen conduit opens, an 35 orificed sleeve movable along said gas conduit, a stem reciprocable in said casing and connected to said sleeve, a valve plug at one end of said stem, means for normally depressing said plug against said seat whereby 40 the orifices in said gas conduit and said sleeve, respectively, register, and means within said casing and responding to increase in pressure therein to raise said stem to partially or entirely close the orifices in 45 the gas conduit.

9. A burner of the character specified,

embodying therein a gas conduit, an oxygen conduit for supplying oxygen, means whereby an auxiliary supply of air may be admitted to said gas conduit, and means 50 whereby said auxiliary air supply is inversely proportioned to said oxygen supply.

10. A burner of the character specified, embodying therein a gas conduit having orifices through which air may be admitted to 55 said gas conduit, an oxygen conduit for supplying oxygen to admix with the gas fed to said gas conduit, and means for varying the area of said orifices in inverse proportion to the quantity of oxygen supplied through 60 said oxygen conduit.

11. A burner of the character specified, embodying therein a gas conduit having orifices through which air may be admitted to said gas conduit, an oxygen conduit for 65 supplying oxygen to admix with the gas fed to said gas conduit, means for varying the area of said orifices relatively to the quantity of oxygen supplied through said oxygen conduit, and means operable to simultaneously operate said first named means 70 and to control the flow of oxygen through said oxygen conduit.

12. A burner of the character specified, 75 embodying therein a gas conduit having orifices through which air may be admitted to said gas conduit, an oxygen conduit for supplying oxygen to admix with the gas fed to said gas conduit, a sleeve movable on said gas conduit for varying the area of the orifices in the latter, a valve for controlling the flow of oxygen through said oxygen conduit, and coöperating means on said sleeve and said valve whereby, upon movement of the latter, said sleeve is actuated to a degree 80 corresponding with the extent of movement of said valve.

FRIEDRICH KRAUSS.
